UNITED STATES PATENT OFFICE

2,317,555

SURFACE ACTIVE AGENT

Hillary Robinette, Terre Haute, Ind., assignor to
 Commercial Solvents Corporation, Terre Haute,
 Ind., a corporation of Maryland

No Drawing. Application November 15, 1941,
 Serial No. 419,317

4 Claims. (Cl. 252—357)

My invention relates to new and useful surface active materials, and more particularly it is concerned with a series of compounds, the general type of which has never been, to my knowledge, recognized as possessing wetting and penetrating properties, as well as other surface active characteristics. Specifically, these compounds are substituted 1,3-dioxanes which may be represented by the following structural formula:

wherein R¹ represents an alkyl group having at least five carbon atoms.

As specific examples of the substituted 1,3-dioxanes which are included by the above generic formula, there may be mentioned 5-amino-2-(3-pentyl)-5-hydroxymethyl-1,3-dioxane, 5-amino-2-hexyl-5-hydroxymethyl-1,3-dioxane, 5-amino-2-(3-heptyl)-5-hydroxymethyl-1,3-dioxane, 5-amino-2-hendecyl-5-hydroxymethyl-1,3-dioxane, 5-amino-2-octyl-5-hydroxymethyl-1,3-dioxane, and the like.

In numerous industries there exists a need for certain types of chemical compounds ordinarily employed in small quantities, to secure an effect which is principally the result of a wetting action, such as the effect obtained by the presence of a surface active agent at a water-oil interface. For example, in the textile and leather-treating industries, there are many situations where wetting or detergent action is highly desirable; as a result, many different agents have been proposed to reduce surface tension and promote wetting. The materials that have been employed in the past, however, although satisfactory in some respects, have not met with unqualified success in all cases.

The ordinary soaps, although their surface active properties have long been recognized, are deficient in many respects when employed in the field of detergent and wetting agents. For example, although soaps act efficiently as detergents in weakly alkaline solutions, they are of no value for this purpose in acid solutions since under such circumstances the free fatty acids, which is insoluble in water, is liberated. In strongly alkaline solutions, on the other hand, ordinary soaps become insoluble and are salted out of solution. In addition, in the presence of

5 solutions containing calcium or magnesium salts, such as ordinary hard water, the fatty acid present in the soap is precipitated as a calcium or magnesium soap, such soaps being insoluble, sticky materials, which, rather than having any detergent action, are regarded as undesirable impurities in solutions employed in the textile and related industries.

In an effort to furnish materials to such industries, free from the undesirable properties of ordinary soaps, there have been developed as detergent and wetting agents, products obtained by the sulfonation of certain fatty acids occurring in oils and fats. Such fatty acids are characterized by containing unsaturated linkages and/or hydroxyl groups in the molecule. On sulfonating such acids, products are obtained which contain sulfuric acid ester groups in the molecule, and of course carboxylic acid groups are attached to the terminal carbon atoms. The products, however, in general possess weaker wetting and detergent properties than soaps. Such products are also relatively unstable and are capable of being decomposed by hydrolysis.

Other proposed wetting agents comprise the semi- and completely-esterified products resulting from the esterification of a higher alcohol with an unsaturated polybasic acid. After the unsaturated esterified acid is produced, it is converted into a more soluble form, ordinarily by treatment with sodium bisulfite to yield the corresponding sulfo derivative of the esterified polybasic acid. While such materials have met with a considerable degree of success in various industries where the need for surface-active materials exists, they are not without certain defects. Obviously surface-active agents of this type are not stable to alkali and in some instances, especially in the textile field, much difficulty has been experienced with the tendency of the textile treating baths containing such materials, to foam.

I have now discovered that aminodioxanes of the class included by the above structural formula serve as highly satisfactory wetting agents, particularly where prior wetting and detergent agents, especially of the type mentioned above, are of little or no value. For example, the wetting agents of the present invention are not decomposed either by hard waters, or solutions containing appreciable quantities of alkali. My new wetting agents possess the further advantage in that aqueous solutions thereof do not foam. In addition, these materials, which are water-white

liquids, are soluble in most of the common organic solvents.

In general, the quantity of the new wetting agents which may be employed will be found to vary with the type of wetting operation under consideration, as well as with the material to be wetted. For most purposes, however, I have found that these wetting agents may be utilized in amounts of from about 0.15 to 0.60 per cent by weight of the treating bath. In this connection, I have found that in many cases it may be desirable to employ a solubilizing material with the wetting agents of the present invention. In such instances, the quantity of wetting agent employed may be reduced, depending of course upon the quantity and type of solubilizing agent employed. Suitable solubilizing materials which may be utilized in combination with my wetting agents, are sulfonated castor oil, sulfonated petroleum oils, sulfonated alkyl aromatic compounds, sulfated esters, sulfated ether-alcohols, sulfonated alkyl diphenyls, soaps and the like.

The wetting power of certain of the aminodioxanes of the present invention is demonstrated by the data appearing in the table below, and was measured by the method of Draves and Clarkson (Am. Assoc. Textile Colorists' and Chemists' Year Book, vol. 17, pp. 216-222 (1940)), which determines the sinking time required for a 5-gram skein of unboiled 2-ply cotton yarn in varying concentrations of aqueous solutions of the aminodioxanes at a temperature of 30° C.

Table

Compound	Grams of amino dioxane per liter	Sinking time
5-amino-2-(3-amyl)-5-hydroxymethyl-1,3-dioxane	6	27
5-amino-2-hexyl-5-hydroxymethyl-1,3-dioxane	3	(1)
5-amino-2-(3-heptyl)-5-hydroxymethyl-1,3-dioxane	1.5	150
5-amino-2-(3-heptyl)-5-hydroxymethyl-1,3-dioxane ¹	2	(1)
	1	35

¹ Instantaneous.

The wetting agents of the present invention may be prepared in accordance with any of several suitable procedures. I prefer, however, to produce such materials by means of the process described in U. S. Patent No. 2,247,256 granted June 24, 1941, to Murray Senkus. In a procedure of this character, the corresponding nitrodioxane is subjected to high-pressure hydrogenation in the presence of a nickel catalyst and a suitable solvent such as methanol, at a temperature in the neighborhood of 25-30° C. The starting materials in this process are conveniently prepared by condensing tris(hydroxymethyl)-nitromethane with any of a number of suitable aldehydes, such as hexanal, heptanal, 2-ethylhexanal, dodecanal, and the like. This condensation reaction is carried out by heating tris(hydroxymethyl)-nitromethane in the presence of the desired aldehyde and a small quantity of an acid catalyst; and, if desired, in the presence of an organic liquid, such as benzene or toluene, which is capable of removing the water produced during the reaction in the form of a constant boiling mixture.

With reference to the compounds covered by certain of the species claims herein, these materials, i. e., 5-amino-2-hexyl-5-hydroxymethyl-1,3-dioxane and 5-amino-2-(3-heptyl)-5-hydroxymethyl-1,3-dioxane, may be synthesized by first

preparing the corresponding nitro dioxane, which involves the condensation of 1 mole of tris(hydroxymethyl)-nitromethane with either 1 mole of hexanal or 1 mole of 2-ethylhexanal, in the presence of a catalytic amount of sulfuric acid. The resulting 5-nitro-2-(3-heptyl)-5-hydroxymethyl-1,3-dioxane or 5-nitro-2-hexyl-5-hydroxymethyl-1,3-dioxane, depending of course, upon the particular aldehyde employed, is then dissolved in methanol and subjected to hydrogenation under a pressure of 2,000 pounds per square inch, at a temperature of between 25-30° C., in the presence of a suitable nickel catalyst, such as Raney nickel.

15 It is understood that applicant does not claim the amino dioxanes per se disclosed and referred to herein, but instead, claims merely a new and novel use of said compounds.

As previously stated, the wetting agents of the present invention may be used alone or in combination with certain solubilizing agents, or other detergents, for cleansing and scouring vegetable and animal fibers when removing fatty or oily materials therefrom. They may also be used as penetrants in flax-retting baths. The penetrating power of these new compositions may be utilized with advantage when said compositions are added to baths containing starchy fermentations which are employed for removing sizing from textile materials. These products function as useful wetting, cleansing and penetrating agents in bleaching liquors, such as those used in the kier boiling of cotton goods, and may be added to the lye liquors used for mercerizing cotton goods. They can also be used to assist in twist setting of yarn and in processes of stripping colors. Such compounds may also be used as assistants in processes of stripping dyes from dyed textile material.

40 A second class of uses of these new surface-active agents is as assistants in the application of dyestuffs. They may be used as dye leveling agents due to their wetting and penetrating properties in neutral or alkaline dyeing baths, and 45 are capable of facilitating dyeing with developed dyes, the dyeing of acetate fibers with insoluble dyes, the dyeing of animal fibers with vat-dyes, the dyeing of various synthetic fibers, and the dyeing of leather.

50 It will readily be seen from the foregoing discussion that by means of the present invention a large group of new surface-active materials has been made available, and that such agents are adapted for use in numerous industrial processes 55 which require surface-active substances. It will also be apparent to those skilled in the art that many widely different embodiments of the present invention exist, and that such embodiments may be utilized without departing from the scope 60 of said invention.

My invention now having been described, what I claim is:

1. In the process for the wet treatment of organic fibrous materials in an aqueous bath, the improvement which comprises incorporating in the bath in an amount to change its surface active properties, an aminodioxane of the formula:

wherein R¹ represents an alkyl group having at least five carbon atoms.

2. In the process for the wet treatment of organic fibrous materials in an aqueous bath, the step which comprises incorporating in the bath in amounts of from about 0.15 to 0.60 per cent by weight of the final solution, an aminodioxane having the formula:

in which R¹ represents an alkyl group containing at least five carbon atoms.

3. In the process for the wet treatment of organic fibrous materials in an aqueous bath, the step which comprises incorporating in the bath 5-amino-2-(3-heptyl)-5-hydroxymethyl-1,3-dioxane.

4. In the process for the wet treatment of organic fibrous materials in an aqueous bath, the step which comprises incorporating in the bath 5-amino-2-hexyl-5-hydroxymethyl-1,3-dioxane.

HILLARY ROBINETTE.
